UNITED STATES PATENT OFFICE

153,213

DESIGN FOR AN EMBROIDERED TRIMMING OR THE LIKE

Maurice Golden, Union City, N. J., assignor to Golden Embroidery Co., Union City, N. J., a copartnership

Application April 5, 1948, Serial No. 145,525

Term of patent 7 years

(Cl. D3—9)

To all whom it may concern:

Be it known that I, Maurice Golden, a citizen of the United States, residing in Union City, county of Hudson, State of New Jersey, have invented a new, original, and ornamental Design for an Embroidered Trimming or the like, of which the following is a specification, reference being had to the accompanying drawing, forming a part thereof.

The figure is a plan view of an embroidered trimming or the like, showing my new design.

I claim:

The ornamental design for an embroidered trimming or the like, substantially as shown.

MAURICE GOLDEN.
